STOCKING

Alfred E. Ischinger, Reading, Pa.

Application April 28, 1950, Serial No. 9,544

Term of patent 14 years

(Cl. D47—7)

To all whom it may concern:

Be it known that I, Alfred E. Ischinger, a citizen of the United States of America, residing at 410 Kenhorst Boulevard, Reading, in the county of Berks and State of Pennsylvania, have invented a new, original, and ornamental Design for a Stocking, of which the following is a specification, reference being had to the accompanying drawings, forming part thereof.

In the drawings:

Fig. 2 is a rear perspective view of the stocking shown in Fig. 1.

I claim:

The ornamental design for a stocking, as shown.

ALFRED E. ISCHINGER.
